UNITED STATES PATENT OFFICE.

CHARLES S. WESTBROOK, OF SPRAGUEVILLE, NEW YORK.

ROCK-DRILL.

SPECIFICATION forming part of Letters Patent No. 312,538, dated February 17, 1885.

Application filed June 16, 1884. (No model.)

To all whom it may concern:

Be it known that I, CHARLES S. WESTBROOK, a citizen of the United States, and a resident of Spragueville, in the county of St. Lawrence and State of New York, have invented certain new and useful Improvements in Rock-Drills; and I do hereby declare that the following is a full, clear, and exact description of the invention, which will enable others skilled in the art to which it appertains to make and use the same, reference being had to the accompanying drawings, which form a part of this specification.

My invention relates to that class of cylinders known as "valveless cylinders," and more particularly to the form of the piston to the cylinder, and to the ports and channels in the cylinder, by which when actuated by suitable power the reciprocating motion of the piston lets in and cuts off the impelling medium and opens and closes the exhaust-ports without the aid of valves.

The object of my invention is to afford a simple and compact apparatus for obtaining motive power and force from steam, compressed air, gas, or other kind of vapor, for use in all classes of engines in which a short rapid forward stroke of the piston is desirable. The object is accomplished by making the cylinder, ports, and piston in the form shown in the accompanying drawings, which represent the invention applied to a rock-drill, and in which—

Figure 1 is a longitudinal sectional view. Fig. 2 is a similar view at right angles to the former view. Figs. 3, 4, and 5 are cross-sections on the lines $x\ x$, $y\ y$, and $z\ z$, Fig. 1.

Similar letters refer to similar parts throughout the several views.

A is a metal cylinder of ordinary construction. In the present case, where the invention is applied to a rock-drill, one head of this cylinder is provided with a stuffing-box, B, Fig. 1, of suitable construction, through which the piston-rod (here the drill-shaft) passes, while through the other cylinder-head is passed the steep-threaded screw and ratchet C, usual in rock-drills, for giving the required turn to the piston and drill. In practice any other suitable device may be substituted therefor, and where the cylinder is used in any other form of motor, except in the case of a steam-

hammer, the steep screw and ratchet will be dispensed with and the piston-rod will work through stuffing-boxes at either or both ends 55 of the cylinder, as may be found convenient. The impelling medium is supplied to the cylinder through the inlet D, which may be of any suitable material and dimensions, opening into the cylindrical side walls of the cylinder A, as shown in Fig. 1. The position of the supply-pipe will be determined by the character of the stroke which the piston is designed to make. In Fig. 1 the supply-pipe is so placed that a line drawn vertically through 65 its center will intersect the central point of the line representing the distance traversed by the piston. It will vary in position according as the stroke of the piston is designed to be slower than the other, as hereinafter 70 specified.

In my invention the piston I is made substantially in the form shown in Fig. 1, with the annular groove or recess k at its center. In practice the piston is cast in one solid 75 piece, of any suitable metal, and turned down in the central position of its cylindrical surface K, so that its diameter there shall be less than at its extremities, as seen in Fig. 4. The length of the piston will vary according to 80 the length of the stroke, size of cylinder, &c.

F and G are two feed-ports cut in the interior side walls and at either end of the cylinder, as shown in Fig. 1, in any convenient longitudinal vertical plane, but preferably in 85 that which intersects the center of the inlet-pipe D, as shown in the views.

For the purpose of diminishing the friction caused by the impelling medium entering the cylinder, a recess, E, is formed in the inner 90 side walls of the cylinder around the inlet-pipe D, as shown, at the point where it enters. The ports F and G are placed at an equal distance from the recess, and are separated therefrom by shoulders or bridges H H. The ports 95 open into the channels or ducts I, which open through the sides of the cylinder into the same at both ends through ports K and L, and the ports and duct and channel leading to the rear end of the cylinder, which is indicated by L, 100 are preferably of larger diameter and capacity than the ports and channel leading to the forward end of the same.

O O are the exhaust-ports, of any convenient

size and shape, which may be placed at any point in the side walls where they will be uncovered by the two piston-heads alternately at the end of each stroke. I prefer, however, 5 to place them, as shown in Figs. 1 and 2, in the vertical plane of the feed-ports. The operation of the cylinder and piston is substantially similar to the operation of the cylinder and piston shown and described in my application for Letters Patent for another rock-drill filed this day in the Patent Office. The impelling medium enters through the inlet-port from which it is conveyed by the recess in the piston to one of the inner ports of the channels, through that channel to the end of the cylinder, where it acts upon the piston, which, in progressing, will cut off the impelling medium, allowing what is left behind it to work by its expansion until the piston uncovers the 15 exhaust-port, when the recess in the piston will connect the inlet-recess with the other channel, causing the piston to return, &c. I am aware that many attempts have been made to construct a cylinder of this character 20 for use in rock-drills, steam-hammers, &c.; but that none have hitherto been invented which have worked successfully. I find, however, that when the feed-ports are so arranged that a greater amount of impelling medium 25 will be supplied to the piston upon the forward stroke than upon the backward stroke, and when the arrangement and disposition of the piston are such that the supply of impelling medium will be cut off at an earlier moment 30 upon the backward stroke than upon the forward stroke, the difficulties heretofore experienced in all valveless cylinders, and particularly when they are applied to rock-drills, will practically cease to exist. These difficulties 35 consist, chiefly, in starting the piston on the return or upward stroke.

By the arrangement of parts heretofore described I am able to leave a small amount of impelling medium in the forward end of the cylinder at the end of the forward stroke, 45 which will be compressed by the blow or stroke of the piston, and enable it to rebound and enter upon its upward or backward stroke, even before the direct supply commences to operate upon the piston. 50

I claim as my invention—

1. In a valveless cylinder for use in rock-drills, steam-hammers, and other forms of engines, the hereinbefore-described combination, consisting of the cylinder, the inlet-port formed into a recess in the inner wall of the cylinder, the feed-ports consisting of channels in the side walls of the cylinder the extremities of which open into its hollow interior at either end and on either side of the inlet and are 60 separated therefrom by shoulders or bridges, the feed-port and channel at the rear end of said cylinder being of larger dimensions and of greater carrying capacity than the forward port and channel, and the exhaust-ports in the 65 side walls of said cylinder.

2. In a valveless cylinder for use in rock-drills, steam-hammers, pumps, &c., the hereinbefore-described arrangement of the cylinder ports and piston, whereby a portion of the 70 impelling medium will be admitted into the forward or lower end of the cylinder before the end of the forward or downward stroke of the piston, for the purposes set forth.

In testimony that I claim the foregoing as 75 my own I have hereunto affixed my signature in presence of two witnesses.

CHARLES S. WESTBROOK.
